DESIGN FOR A PEN STAND

Sidney M. Massee, Cleveland, Ohio

Application November 9, 1933, Serial No. 49,680

Term of patent 14 years

To all whom it may concern:

Be it known that I, Sidney M. Massee, a citizen of the United States, residing at 807 Cuyahoga Building, in the city of Cleveland, county of Cuyahoga, and State of Ohio, have invented a new, original, and ornamental Design for Pen Stands, of which the following is a specification, reference being had to the accompanying drawing, constituting a part thereof.

The figure is a perspective view of a pen stand showing my new design.

I claim:

The ornamental design for a pen stand substantially as shown.

SIDNEY M. MASSE.
